UNITED STATES PATENT OFFICE

EWALD MEININGHAUS, OF LANCASTER, NEW YORK

LATCH

Application filed January 25, 1929. Serial No. 335,038.

This invention relates to a latch for swinging doors or windows and more particularly to a device which will hold the door or window ajar so as to provide adequate ventilation 5 without a draft, such a device being applicable for use on automobiles or in the doors of houses to hold the doors open and provide fresh and cool air without liability of the doors swinging shut.

10 One of the principal objects of this invention is to provide such a latch which automatically locks a swinging door or window in the desired open position upon opening the same and which can be easily released to permit of closing the door or window.

A further aim is to provide such a device which is inexpensive, simple, compact and strong, and will not get out of order or out 20 of good working condition through constant or severe use.

Another purpose is to provide such a latch which is adapted for use on a swinging door or window which swings either to the right or to the left by means of a very simple reorganization of the parts when such reorganization is necessary.

A still further object is to provide such a device which is attractive in appearance and occupies but a small space on the frame of 30 the door or window.

In the accompanying drawings:

Figure 1 is a fragmentary side elevation of a door and door frame showing my invention applied thereto, the door being shown in its 35 closed position.

Figure 2 is a fragmentary top plan view of a door frame and door showing my latch applied thereto, the latch being shown in the position in which it holds the door against closing, a partially closed position of the latch and door being shown in dotted lines.

Figure 3 is a horizontal section through the door and door frame taken on line 3—3, Fig. 45 1, looking upwardly.

Figure 4 is a fragmentary longitudinal section of my latch taken on line 4—4, Fig. 3.

Figure 5 is a transverse section, taken on line 5—5, Fig. 4.

50 Similar characters of reference indicate

like parts in the several views of the drawings.

In its general organization this invention is adapted for use in holding two relative swinging members ajar and includes an arm 55 pivoted to one of said members, a second arm pivotally connecting the first arm and the other of said members and a latch bar carried by one of the arms and adapted to catch and hold the other arm when the members are 60 opened and prevent a return or folding movement of the arms except when the catch is released.

In the accompanying drawings, the invention is shown as applied to a door D which is 65 hung in a door frame F by means of the usual hinges H. A plate 10 is suitably secured to the underside of the top bar of the door frame F and is formed to provide a pin 11 which projects downwardly and pivotally supports 70 the inner end of an arm 12. This arm 12 is preferably made of flat bar stock and is pivotally connected to a second arm 13 by means of a pivot pin 14. The other end of the arm 13 is pivotally connected to a bracket 15 which 75 is suitably secured to the side of the door D. As best shown in Fig. 2 the end of the arm 13 is connected to an intermediate portion of the arm 12, the arm 12 thereby having an outwardly projecting end 16 which in the extended or unfolded portion of the arms overlaps the arm 13.

It is apparent that when the door is opened the arms will be unfolded or moved into straightened relation to one another and that 85 when the door is closed the arms will be collapsed or folded as indicated by dotted lines in Fig. 2 and will fold into a position immediately below the door frame as indicated in Fig. 3. In order to hold the arms against folding when the door has been swung open to the position shown in Fig. 2, a catch is provided which is preferably constructed as follows:

As best shown in Fig. 4 the pivot pin 14 95 which connects the two arms 12 and 13 is formed at its lower end to provide a rounded head or seat 17 and also a downwardly projecting neck 18 at the lower end of this head. To this neck 18 a catch bar 19 is secured, this 103

catch bar being sufficiently loosely mounted on the neck 18 so that it is free to rock upon the rounded head or seat 17. This catch bar extends along the outwardly projecting end 5 16 of the arm 12 and preferably projects beyond the end thereof so as to form a finger piece 20 by means of which the catch bar can be moved away from the end 16 of the arm 12. If desired a chain 21 can be attached to 10 the finger piece 20 for the purpose of moving this catch bar downwardly.

The end 16 of the arm 12 is provided with a threaded opening which receives a screw 22, the end of this screw projecting upwardly into the path of the other arm 13 and thereby limiting the opening movement of these arms relative to each other and preventing the arms from passing beyond their dead center. This screw 22 also extends 15 through an opening in the catch bar 19 and between the head at the lower end of this screw 22 and the catch bar 19 a helical compression spring 23 is interposed. It is therefore apparent that the catch bar is yielding- 20 ly held in its elevated position against the underside of the projecting end 16 of the arm 12 by the tension of the spring 23 and can only be moved downwardly by manually 25 pulling upon the chain 21 or depressing the finger piece 20.

The catch bar 19, as best shown in Fig. 3 is T-shaped, the same being formed to provide laterally extending wings 24. At the outer end of each of these wings 24 a catch 30 projection 25 is formed, these catch projections being formed to provide rounded faces 26 on their outer sides and abrupt faces 27 on their inner sides.

It is therefore apparent that when the 35 door is opened the arms 12 and 13 will unfold or straighten until the arm 13 is moved adjacent the rounded face 26 of the catch projection 25 on the corresponding side of the catch bar 19. Upon then opening the door further the arm 13 engages the rounded face 26 of the catch projection on the corresponding side of the catch bar and forces the catch bar downwardly against the resistance of its return spring 23 and rides over 40 the catch projection. The arm 13 then strikes the upper end of the screw 22 which prevents its further movement and also prevents the arms 12 and 13 from passing beyond their dead center. In this position of 45 the arms the arm 13 is arranged between the screw 22 and the square shoulder 27 of the catch projection 25 so that the door is securely held both against further opening movement and against closing movement.

When it is desired to close the door the 50 finger piece 20 of the catch bar is depressed either directly or by pulling down upon the chain 21. This movement of the catch bar moves the catch projections 25 out of the path 55 of the arm 13 and permits the arms to col-

lapse and the door to be closed as indicated by dotted lines in Fig. 2.

It is apparent that by the provision of the screw 22 and two catch projections 25 on the catch bar 19 that the devices can be applied to doors which swing either to the left or to the right. Thus if the device is to be applied to a door which swings to the opposite side as compared with the door shown in the drawings, the screw 22 is unscrewed from the projecting end 16 of the arm 12 until the arm 13 can be moved over to the opposite side of the screw. The screw 22 is then screwed up to form a stop projection for limiting the movement of the bar 13. It is apparent that with the bar 13 on the opposite side of the screw 22 that the device can be applied to a door swinging in the opposite direction from the door for which the device was adapted for use in the first instance.

It is obvious that by the provision of a pivot pin forming a rounded seat for the catch bar, as indicated, that a very simple and inexpensive and also easily working mounting is provided for the catch bar which insures its free action at all times.

As a whole this invention provides a very simple, inexpensive, compact and strong device for holding a swinging door or window in an open position and will reliably function for a long time without liability of getting out of order or working imperfectly.

I claim as my invention:

1. A latch for two relatively movable members, comprising an arm pivotally connected to one of said members, a second arm pivotally connected to the other member and said first arm, a catch bar movably mounted on one of said arms and spring means yieldingly holding said catch bar against the arm on which it is mounted, said catch bar being provided with a catch projection arranged in the path of the other arm and adapted to catch and hold said last named arm in fixed relation to the first arm.

2. A latch for two relatively swinging members, comprising an arm pivotally connected to one of said members, a second arm pivotally connected to the other member and said first arm, a catch bar movably mounted on one of said arms, and means yieldingly holding said bar against the arm on which it is mounted, said catch bar being provided with a catch projection arranged in the path of the other arm, said catch projection permitting said other arm to ride thereover when said arms are extended and thereafter preventing a folding movement of said arms.

3. A latch for two relatively swinging members, comprising an arm pivotally connected to one of said members, a second arm pivotally connected to the other member and said first arm, a catch bar movably mounted on one of said arms, means yieldingly holding said bar against the arm on which it is

5 mounted, said catch bar being provided with a catch projection arranged in the path of the other arm, said catch projection permitting said other arm to ride thereover when said arms are extended and thereafter preventing a folding movement of said arms, and means for manually moving said catch bar to permit said arms to be folded.

10 4. A latch for two relatively swinging members, comprising an arm pivotally connected to one of said members, a second arm pivotally connected to the other member and said first arm, a catch bar movably mounted on one of said arms, means yieldingly holding said bar against the arm on which it is mounted, said catch bar being provided with a catch projection arranged in the path of the other arm, said catch projection permitting said other arm to ride thereover when 15 said arms are extended and thereafter preventing a folding movement of said arms, and means for preventing said arms from passing beyond their dead center.

20 5. A latch for two relatively swinging members, comprising an arm pivotally connected to one of said members, a second arm pivotally connected to the other member and pivotally connected between its ends to the other arm thereby to provide portions of said 25 arms which overlap in the unfolded position of said arms, a catch bar movably secured at one end to the outer side of one of said arms and having a projection arranged in the path of the overlapping portion of the other arm 30 and adapted to catch and hold said overlapping portion of the other arm when said arms are unfolded, and means for preventing said arms from passing beyond their dead center.

35 6. A latch for two relatively swinging members, comprising an arm pivotally connected to one of said members, a second arm pivotally connected to the other member and pivotally connected between its ends to the other arm thereby to provide portions of said 40 arms which overlap in the unfolded position of said arms, a catch bar movably secured at one end to the outer side of one of said arms and having a projection arranged in the path of the overlapping portion of the other arm 45 and said projection being adapted to catch and hold said overlapping portion of the other arm when said arms are unfolded and means for preventing said arms from passing beyond their dead center, comprising a 50 removable bolt carried by one of said arms and projecting into the path of the other arm.

55 7. A latch for two relatively swinging members, comprising an arm pivotally connected to one of said members, a second arm pivotally connected to the other member, a pivot pin extending through said arms and connecting one of said arms with an intermediate portion of the other arm thereby to provide portions of said arms which overlap in the unfolded position of said arms, a catch 60

bar mounted on the outer side of one of said arms for movement toward and from said arm, said catch bar being provided with a catch projection adapted to catch the overlapping portion of the other arm when said arms are unfolded and prevent their reverse movement, a screw extending through said catch bar and the arm on which said catch bar is mounted and arranged in the path of the overlapping portion of the other arm to prevent movement of said arms beyond their dead center and a helical spring interposed between the head of said screw and said catch bar.

70 8. A latch for two relatively swinging members, comprising an arm pivotally connected to one of said members, a second arm pivotally connected to the other member, a pivot pin extending through said arms and connecting one of said arms with an intermediate portion of the other arm thereby to provide portions of said arms which overlap in the unfolded position of said arms, a catch bar mounted on the outer side of one of said arms for movement toward and from 75 said arm, said catch bar being provided with a pair of catch projections adapted to catch the overlapping portion of the other arm when said arms are unfolded and prevent their reverse movement, and a screw extending through said catch bar and the arm on which said catch bar is mounted and arranged in the path of the overlapping portion of the other arm to prevent movement of said arms beyond their dead center.

80 9. A latch for two relatively swinging members, comprising an arm pivotally connected to one of said members, a second arm pivotally connected to the other member, a pivot pin extending through said arms and connecting one of said arms with an intermediate portion of the other arm thereby to provide portions of said arms which overlap in the unfolded position of said arms, a catch bar loosely secured at one end to the pivot pin 85 connecting said arms, said catch bar being provided with catch projections adapted to catch the overlapping portion of the other arm when said arms are unfolded and prevent their reverse movement and spring 90 means for holding said catch bar in its operative position.

10. A latch for two relatively swinging members, comprising an arm pivotally connected to one of said members, a second arm pivotally connected to the other member, a pivot pin extending through said arms and connecting one of said arms with an intermediate portion of the other arm thereby to provide portions of said arm which overlap 100 in the unfolded position of said arms, said pivot pin being formed to provide a rounded head and a neck projecting outwardly from said head, a catch bar having an opening at one end through which said neck projects,

said catch bar being seated on said rounded head to permit movement of said catch bar toward and from said arms, and spring means tending to hold said catch bar against the adjacent arm, said catch bar being provided with a catch projection adapted to catch the overlapping portion of the other arm when said arms are unfolded thereby to prevent their reverse movement.

- 10 11. A latch for two relatively swinging members, comprising an arm pivotally connected at one end to one of said members, a second arm pivotally connected to the other member, a pivot pin having a rounded head, 15 connecting the end of said first arm with an intermediate portion of said second arm, said second arm thereby having its end projecting beyond said pivot pin, a catch bar mounted for rocking movement on said rounded head, 20 a screw secured to said projecting end and extending through said catch bar, the end of said screw extending into the path of said first arm and limiting the opening movement of said arms, a spring interposed between the 25 head of said screw and said catch bar, and catch projections formed on opposite sides of said catch bar and projecting outwardly along opposite sides of said projecting end, said catch projections being adapted to catch 30 and releasably hold said first arm, thereby to prevent said arms from folding.

In testimony whereof I hereby affix my signature.

EWALD MEININGHAUS.
